BOOK DRYING APPARATUS

Arthur Crawley III, Cincinnati, Ohio, assignor to Crawley Book Machinery, Inc., Newport, Ky., a corporation of Kentucky

Filed Jan. 21, 1965, Ser. No. 426,947

15 Claims. (Cl. 34—236)

This invention relates to an apparatus for applying heat to freshly glued and assembled books so as to dry the adhesive which secures the book covers to the book fillers.

Generally speaking, in the manufacture of books, each page block or filler, comprising the printed leaves of the book, are assembled by stitching, or in some cases by a gluing operation. Each book cover is assembled as a separate unit, subsequently to be applied to the book filler by a gluing operation. After fabrication of the book fillers and covers, each filler is inserted within a cover, with wet adhesive applied to the rounded end portion of the filler and also to the flat sides of the filler (or to the corresponding surfaces of the cover) to provide an adhesive bond between the meeting surfaces of the filler and cover. After the application of the adhesive, the filler is slipped into the cover so as to bring the adhesive surfaces of the sides and the rounded end of the book filler into contact with the corresponding surfaces of the book filler.

In one procedure (used extensively in the past) the assembly of the books is completed by stacking the books between pressboards, each having a ridge or rib projecting from opposite sides. In fabricating books by this method, the freshly glued books are placed between pairs of pressboards, with the ribs extending along the covers adjacent the rounded ends, with pressure applied to the pressboards. In this method of fabrication, the ridges impress the crease lines adjacent the rounded end of the books so as to draw the covers under pressure into engagement with the rounded ends of the book fillers, while the pressboards hold the flat sides of the covers into pressure engagement with the opposite side of the book fillers.

In order to speed up the assembly operation, various types of power machines have been developed to press and crease freshly glued assembled books in a rapid continuous manner, such that the pressing and creasing (or nipping) mechanism may form a part of a production line for the assembly of books in a continuous manner.

According to this system, the books are glued and assembled in a machine known in the industry, as a casing-in machine, then they are advanced to a pressing and creasing machine where a series of nippers or creasers act upon the rounded end portions of the books to draw the cover assembly into intimate engagement with the rounded edge of the book. In passing through this machine, respective sets of presser plates also act upon the flat sides of the book covers to force the covers into intimate engagement with the sides of the book filler. A machine of this type is disclosed in the patent issued to Arthur Crawley et al., No. 2,921,322.

After passing through the pressing and creasing machine, the books are advanced in a continuous stream through the dryer apparatus of the present machine. It will be understood, at this point, that, as the books issue from the pressing and creasing machine, the cover is, at least in a preliminary way, bonded to the rounded end of the filler and also to the opposite sides of the filler. However, the assembled books require further heat treatment before they are in condition to be placed on the market.

One of the primary objectives of the present invention has been to provide a book drying apparatus which is adapted to receive a continuous stream of books issuing

2

from a book pressing and creasing machine and adapted to apply radiant heat, particularly to the rounded ends of the books, during advancement, thereby to provide a permanent bond between the cover and rounded end of the book.

5 According to this aspect of the invention, the books issuing from the pressing and creasing machine pass to a conveyor system comprising a pair of chains having spaced transverse book support bars which engage the rounded ends of the books. The conveyor system advances with respect to a series of radiant heating elements, mounted beneath the conveyor, which apply radiant heat to the rounded ends of the books as they are advanced, thereby to complete the adhesive drying action.

10 A further objective of the invention has been to provide a drying apparatus which is of relatively compact design so as to be capable of installation in book binding plants, particularly those in which the floor space is limited.

15 It will be understood that, in order to provide the required drying period for the heating elements to act upon the freshly glued, rounded ends of the advancing books, the dryer apparatus necessarily must be of considerable length. However, in order to provide a practical apparatus for installation in an average plant, the present machine is provided with a plurality of conveyor runs, angularly related to one another to conserve space. Each conveyor run includes a book-receiving end and a book-discharge end, the discharge end of one run being adjacent the receiving end of the next run. The discharge and receiving ends of the conveyor runs communicate with one another by means of one or more turntables which rotate at a substantially the same rotary speed as the lineal speed of the conveyor runs, and arranged to transfer the book from the downstream end of one conveyor run to the upstream end of the companion conveyor run.

20 By virtue of this arrangement, the conveyor runs may be arranged in generally V-shaped formation comprising two conveyor runs connected by a turntable; in another example the runs may be arranged in zigzag or switchback formation comprising three or more runs connected by means of several turntables; in still another form of the invention, the conveyor system may comprise two runs 25 extending in the same direction but displaced laterally from one another and connected by a third transverse run, such that the three conveyor runs are interconnected with one another by means of two turntables.

25 A further objective of the invention has been to provide a dryer apparatus which is adjustable so as to accommodate books of various sizes and thicknesses.

30 Generally speaking, the books, which advance with their rounded ends resting upon the conveyor runs, are supported in upright position by means of parallel guide plates spaced apart from one another and rising upwardly along opposite sides of the conveyor run. The parallel guide plates interconnect with arcuate guide plates which extend around the turntables in generally concentric relationship so as to guide the books in the upright position in their arcuate path of motion about the turntable from the downstream end of one conveyor run to the upstream end of the next conveyor run.

35 In order to accommodate the various sizes of books (variations in length and width) the longitudinal guide plates of the conveyor runs, and also the arcuate guide plates of the turntables, are mounted for transverse adjustment with reference to one another. According to this aspect of the invention, the drying apparatus may be set up to handle any of the various sizes of books for 40 which the pressing and creasing machine is designed.

45 The various features and advantages of the invention will be more fully apparent to those skilled in the art

from the following detailed description taken in conjunction with the drawings.

In the drawings:

FIGURE 1 is a diagrammatic plan view illustrating in a general way, one arrangement of the present book conveyor system in relation to the conveyor runs of the book drying apparatus.

FIGURE 2 is a diagrammatic plan view, generally similar to FIGURE 1, illustrating a second form of the book conveyor system in relation to the book drying apparatus. The conveyor system of FIGURE 2 has been selected as a typical example to illustrate the principles of the invention in the specification.

FIGURE 3 is a diagrammatic plan view similar to FIGURE 2, showing another typical arrangement of the conveyor system in relation to the sections of the book drying apparatus.

FIGURE 4 is a fragmentary side elevation of the conveyor system of FIGURE 2, including one of the turntables which transfer the books from one conveyor run to another.

FIGURE 5 is a top plan as viewed along line 5—5 of FIGURE 4, illustrating the power motor and transmission system which drive the conveyor system and turntables.

FIGURE 6 is a fragmentary top plan as viewed along the line 6—6 of FIGURE 4, illustrating the conveyor system and turntables shown in FIGURE 4. FIGURES 4 and 6 correspond with the conveyor system shown diagrammatically in FIGURE 2.

FIGURE 7 is a fragmentary enlarged plan, taken from the left hand end of FIGURE 6, detailing the end portion of the book conveyors, elevating paddlewheels, turntables, and adjustable turntable guides which adapt the conveyor system and turntable to books of different lengths and thicknesses.

FIGURE 8 is a fragmentary view taken along line 8—8 of FIGURE 7, further detailing the turntable in relation to the conveyor runs, with parts broken away to bring out more clearly certain features of the mechanism.

FIGURE 9 is a sectional view taken along line 9—9 of FIGURE 8, detailing one of the turntables and the driving system which connects the turntable to the conveyor system for rotary motion.

FIGURE 10 is an enlarged sectional view taken along line 10—10 of FIGURE 4, detailing a portion of the book conveyor system in relation to the heater tubes which act upon the freshly glued, rounded ends of the books.

FIGURE 11 is an enlarged fragmentary sectional view taken from FIGURE 10 and detailing one of the cross rods of the conveyor system which support the rounded end of the book with reference to the heating elements which extend longitudinally in the conveyor runs.

FIGURE 12 is a sectional view taken along line 12—12 of FIGURE 7, detailing one of the paddlewheel assemblies which lift the advancing books from the end portion of the conveyor run to the turntable and which lowers the books back to the adjacent conveyor run after passage about the turntable.

FIGURE 13 is a sectional view taken along line 13—13 of FIGURE 12, illustrating the structural details of one of the paddlewheels.

General arrangement

The principles of the book drying apparatus of this invention are disclosed generally in FIGURES 1—3. As noted later, the system disclosed in FIGURE 2 has been selected as a typical example in the detailed drawings and disclosure. However, it will be understood that the same principles are utilized in the examples which are illustrated in FIGURES 1 and 3.

As explained earlier, the dryer apparatus necessarily has a considerable length in order to provide the re-

quired drying period during which the heating elements act upon the freshly glued, continuously advancing books. The three typical examples have been illustrated to bring out the variations in the conveyor system and heating sections adapted to fit within the floor space of various book binding plants.

In the manufacture of books, as indicated earlier, each page block or filler, as one step in the operation, is assembled as a unit by stitching or the like. Each book cover is also fabricated as a separate unit, later to be applied to the filler. In general, the book is assembled by applying wet adhesive to the rounded end portion of the filler and to the sides of the filler (or to the meeting surfaces of the book cover) then the filler is slipped into the cover so as to bring the adhesive surfaces into contact with one another.

After this operation, the assembled books are advanced through a book pressing and creasing machine which includes flat plates or smashers engageable with the opposite sides of the book cover; the machine further includes creasers or nippers which engage the lower edge portion of the book adjacent the rounded end thereof.

The purpose of the smashers or presser plates is to force the freshly glued book covers into intimate contact with the opposite sides of the book cover to primarily form an adhesive bond therebetween. The purpose of the nippers is to draw the flexible portion of the cover into intimate contact with the rounded end of the book to form a preliminary adhesive bond between the rounded end of the book and the rounded portion of the cover. After the smashing and nipping operation, each book is advanced to the continuously advancing conveyor of the drier assembly of this invention for the application of heat, particularly to the rounded end of the book so as to set the adhesive before the book is discharged from the machine.

In the form of the invention shown in FIGURE 1, the conveyor system is generally V-shaped, comprising two conveyor runs angularly related to one another. The ends of the conveyor system, as explained later, are in connection with one another by a turntable constructed in accordance with this invention.

The arrangement shown in FIGURE 2 utilizes the same principles as shown in FIGURE 1; however, in this case, the conveyor system is of the switchback type, wherein the books are discharged through a zigzag path.

In the form disclosed diagrammatically in FIGURE 3 the conveyor system comprises two runs displaced laterally from one another and connected by a transverse conveyor run. The systems illustrated in FIGURES 1—3 represent typical arrangements which are adapted to accommodate different book binding plants.

Arrangement of first system (FIGURE 1)

Referring to FIGURE 1, the section designated as a nipper-gluer, indicated generally at 1, represents both the primary assembling machine, within which the page block or filler, with liquid glue applied, is slipped into the book cover. The section 1 also represents the book smashing and nipping machine, within which the opposite sides of the book cover are forced under pressure engagement against the opposite sides of the book filler so as to establish intimate engagement between the glued surfaces. This section also includes the creasers or nippers which impress the crease into the opposite sides of the book adjacent its rounded end so as to pull the rounded portion of the cover into intimate engagement with the rounded end of the book, thereby to bring the glued surfaces into intimate contact with one another in this area.

Upon being discharged from the smashing and nipping mechanism 1 (FIGURE 1), each book is advanced to a conveyor system, indicated generally at 2, having a first run 3 which advances in the direction indicated by the arrow, which advances each book continuously through

a predryer section indicated generally at 4. The predryer section 4 includes heating elements extending longitudinally beneath the conveyor and arranged to project relatively high temperature heat rays to the rounded end of the book to provide a preliminary drying action.

After passing through the predryer, the books are advanced continuously above a series of radiant heating elements which extend longitudinally beneath the conveyor between the predryer and the turntable, which is indicated generally at 5, which rotates in the direction indicated by the arrow. Upon reaching the turntable 5, each book is lifted from the conveyor 2 to the turntable which carries the book in an arc, then lowers the book to the second run 6 of the conveyor system. The second run 6 of the conveyor system, as indicated by the arrow, receives the books after they have passed through an arc about the turntable 5, then advances the books in the direction indicated by the arrow toward the discharge portion of the machine 7.

The discharge portion 7 of the machine comprises, in the present example three sections comprising a renipper mechanism 8, a counter and stacker 10, and a book gathering mechanism 11 having a discharge end 12.

The renipper mechanism 8 includes opposed sets of creaser jaws or nippers which apply pressure to the creased edge of each book adjacent its rounded end, providing a finishing operation with reference to a rounded end; the counter and stacker mechanism 10 and book gathering mechanism 11 collect the books for discharge from the machine.

It will be noted that the system disclosed in FIGURE 1 is so arranged that the books, which are fed into the nipper-gluer 1 at the upstream end of the conveyor system 2, are discharged at the downstream end as at 12, laterally displaced from the upstream end of the conveyor. This system is designed to accommodate one given type of plant layout.

It will be understood at this point, that the invention is directed to the dryer assembly comprising conveyor system 2, in combination with the turntable 5 and coacting elements. For this reason, a detailed disclosure of the nipper-gluer 1 at the upstream end of the conveyor system 2 and of the discharge portion 7 at the downstream end have been omitted from this disclosure. The structural details of the conveyor system, which is common to the three systems illustrated (FIGURES 1-3) are disclosed at a later point in this specification.

Arrangement of second system (FIGURE 2)

In the system disclosed diagrammatically in FIGURE 2, the nipper-gluer, indicated generally at 1, is similar to the corresponding mechanism shown in FIGURE 1, and the discharge portion 7 is also similar. In this installation, the conveyor system 2 is of switchback or zigzag formation, comprising an upstream run 13, a return run 14, and a downstream run 15 leading to the discharge portion 7. In this conveyor system, there is provided a first turntable 16 providing connection between the upstream run 13 and downstream run 14. A second turntable 17 provides connection between the return run 14 and downstream run 15.

The run 13 of the conveyor system 2 includes a predryer section 4, having high temperature heating elements (not shown). The conveyor run 13, 14 and 15 also include radiant heating elements extending longitudinally of the conveyor runs, as described above with reference to FIGURE 1.

The conveyor system of FIGURE 2 is adapted to reduce the length of the dryer assembly while still providing a sufficient time period for the glue drying operation. In this arrangement, the freshly glued books are fed into the apparatus at one end and are discharged at the opposite end of the machine, as distinguished from the system shown in FIGURE 1.

Arrangement of third system (Figure 3)

The dyer apparatus shown diagrammatically in FIGURE 3 is also similar in principle to arrangements shown in FIGURES 1 and 2. However, in this instance the nipper-gluer 1 is located at the opposite side of the plant and the discharge portion 7 is displaced laterally. In this arrangement, the conveyor system 2 includes an upstream run 18, a lateral run 20 and a downstream run 21. A first turntable 22 transfers the books from the upstream run 18 to the lateral run 20 and a second turntable 23 transfers the books from the lateral run 20 to the downstream run 21. The conveyor system 2 also includes a high temperature predryer 4 with radiant heating elements extending longitudinally along the conveyor runs 18, 20 and 21. The books are advanced from the nipper-gluer 1 in the direction indicated by the arrows to the discharge portion 7.

Conveyor and driving system (Figures 2 and 4-13)

As noted earlier, the three typical arrangements of the dryer mechanism, illustrated in FIGURES 1-3, all utilize the same principles of operation. However, the system shown diagrammatically in FIGURE 2 has been selected as a typical example of the invention. The following detailed description therefore is made with reference to the arrangement shown diagrammatically in FIGURE 2 and the related detailed views (FIGURES 4-13).

As shown in FIGURES 4 and 6, the apparatus which has been selected to illustrate the principles of this invention, comprises the switchback or reverse bend conveyor system illustrated diagrammatically in FIGURE 2, utilizing the first and second turntables 16 and 17, previously described. As noted earlier, this conveyor system comprises the upstream run 13 leading from the nipper-gluer section, previously indicated at 1, to the first turntable 16. The turntable 16 advances the freshly glued books through an arc of 180° to the return or switchback run 14 which carries the books to the second turntable 17. The second turntable 17 carries the books through another half turn (180°) and delivers them to the downstream run 15 for advancement to the discharge section 12 of the machine. It will be understood that the runs 13, 14 and 15 of the conveyor system 2 need not be disposed in parallel relationship; in other words, the runs may be related to one another at other angles, as dictated by the layout of the plant in which the machine is installed.

Described in detail (FIGURES 4-6), the book drying apparatus, selected to illustrate the invention, comprises in general, a frame structure, indicated generally at 24 comprising vertical legs 25 having horizontal rails 26 which support the chains of the conveyor system 2, previously indicated in FIGURE 2. The conveyor system (FIGURES 4-6) is driven by a power motor 27 mounted upon a platform 28, which is attached to the frame 24 of the conveyor system at the end of the downstream run 15 of the conveyor system 2. The motor 27 is connected by a belt or chain 30 to a speed reduction unit 31 which is in driving connection with the conveyor system 2 (FIGURE 5).

The conveyor system is connected to the speed reduction unit 31 by way of a sprocket chain 33 meshing with a sprocket 32 of the speed reduction unit 31. Chain 33 passes around a sprocket 34 which is mounted upon a cross shaft 35 journaled in the machine frame 24 (FIGURES 4 and 5). Shaft 35 includes a pair of sprockets 36-36 (FIGURE 5) which advance the chains 37-37 of the conveyor system 2.

It will be understood at this point that the entire conveyor system, including the turntables 16 and 17 (FIGURE 6) are driven by the power motor 27 through the speed reduction unit 31. It will also be understood that a similar power motor and speed reduction unit is utilized in driving the conveyor system and turntables in the drying apparatus which is illustrated in FIGURES 1 and

3. In each instance, the several runs of the conveyor system are interconnected with one another through a driving system which rotates the turntables in time with the advancement of the conveyor runs, as explained later in detail.

The conveyor chains 37—37 (FIGURE 10) are supported upon rails 38—38 which are carried by angle irons 40—40 attached to the frame 24 of the machine. Each chain 37 includes lugs 41—41 (FIGURES 10 and 11) rising upwardly from the respective chains 37, and arranged in pairs on the respective chains 37. The upper ends of the pairs of lugs 41—41 are bored to receive the opposite ends of cross rods, indicated generally at 42—42, which are clamped in place by pairs of nuts 43 (FIGURE 11).

Each cross rod 42 includes a covering of plastic material 44 which is arranged to support and advance the rounded end 45 of the book 46, as indicated in FIGURE 10.

As viewed in FIGURE 7, the cross rods 42 are spaced apart from one another to support the books; on the other hand, the rods 42 do not interfere with the action of the radiant heaters, which are mounted beneath the conveyor runs and arranged to project heat rays upon the rounded ends 45 of the books.

As noted earlier, the predryer section 4 (FIGURE 2) comprises a series of conventional high temperature electrical heating elements adapted to project radiant heat upon the freshly glued, rounded ends 45 of the books as they issue from the nipper-gluer section 1 of the machine. These heating elements are of conventional design and have not been disclosed in detail.

After passing beyond the predryer section 4, the books are advanced by the conveyor system 2 above a series of radiant heat lamps, indicated generally at 47 (FIGURE 10). The heat lamps 47 have substantial length and are arranged longitudinally in series with one another beneath the runs (runs 13, 14 and 15—FIGURE 2) of the conveyor system. In order to direct the heat rays, the heat lamps 47 are provided with reflectors 48 (FIGURE 10) facing upwardly toward the rounded ends 45 of the books. The heat lamps and reflectors are supported by cross bars 50, which in turn, are supported by hangers 51 which are attached to the frame 24 of the machine (FIGURE 10).

As noted earlier, the several runs 13, 14 and 15 of the conveyor system 2 are all driven by the motor 27 and speed reduction unit 31. The power is transmitted from the power motor 27 and speed reduction unit 31 to the first conveyor run 15 (downstream) as shown in FIGURE 6. The return or switchback run 14 is driven by downstream run 15 through the second turntable 17 and upstream run 13 is driven by the switchback run 14 through the first turntable 16, as explained in detail later. The driving connection through the turntable is identical for each run and is disclosed in detail in FIGURE 9, which represents the drive through the first turntable 16 (FIGURE 2).

As best illustrated in FIGURE 4, each conveyor run 13, 14 and 15 is in the form of an endless loop which includes upper or book transport section (chains 37—37 and cross rods 42—FIGURE 10). Each conveyor chain loop includes an idler run 52 which depends in slack condition below the upper or active run of the conveyor.

As indicated generally in FIGURES 7—8 (first turntable 16), the chains 37 of switchback run 14 pass idler sprockets 53—53 which are keyed to a cross shaft 54 journaled as at 55 upon the frame 24. The driven cross shaft 54 drives the turntable 16, as explained later.

Briefly, each conveyor run 13, 14 and 15 comprise an individual loop consisting of the parallel chain runs 37—37, with slack return runs 52—52. In other words, each conveyor run 13, 14 and 15 comprises a self-contained unit; however, the three runs are driven from one another

by the power motor 27 (FIGURES 4 and 5) and through the turntable 16 and 17 in time with one another and in time with the rotary motion of the turntables.

As best shown in FIGURES 6 and 10, each conveyor run 13, 14 and 15 includes a longitudinal guide passageway, indicated generally at 56, adapted to slidably support the books 46 in their vertical position upon the cross rods 42 for advancement with reference to the predryer section 4 and radiant heat lamps 47. In order to accommodate the machine to the thickness of various books which are advanced through the machine, the longitudinal passageway 56 is adjustable transversely.

Described in detail (FIGURES 6 and 7) each longitudinal guide passageway 56 communicates with arcuate guide passageways, indicated generally at 57, which connect with the longitudinal guide passageways 56 so as to guide the books through their arcuate path about the turntable from one longitudinal conveyor run to another.

Described in detail (FIGURES 7—10), each longitudinal guide passageway 56 comprises a pair of spaced guide plates 58—58, the plates having inset lower portions 60—60 adapted to slidably embrace the lower portion of the book 46, immediately above the rounded end 45. In order to stiffen the plates 58, the lower edge of each plate is provided with a right angular flange 61. The upper edge of each plate 58 includes an angular flange 62 to further stiffen the plate and to facilitate handling of the books 46, should this be necessary.

In order to compensate for the thickness of the books, each guide plate 58 is adjustably supported upon a bracket 63 (FIGURE 10) rising from the frame 24 of the machine. The upper end of each bracket 63 is bored to slidably receive a mounting rod 64. The inner end of each mounting rod 64 is attached as at 65—65 to its guide plate 58. The guide plates are locked in their transversely adjusted position by means of screws 66—66 which are threaded through the brackets 63 and into engagement with the mounting rods 64—64.

It will be noted that each conveyor run is provided with a series of brackets 63 (FIGURE 4), the arrangement being identical for each of the conveyor runs 13, 14 and 15. As explained later in detail, each longitudinal guide passageway 56, as delineated by the guide plates 58—58, communicate with the arcuate guide passageways 57 (FIGURES 6 and 7) which guide the books about the first and second turntables 16 and 17.

Turntable and paddle wheel drive

As indicated previously, the turntable 16 and 17 and the associated paddle wheels, indicated generally at 69, are identical in construction. The turntable and paddle wheel for each run are driven by the conveyor system, such that each associated paddle wheel and turntable advance in time with the conveyor system 2.

Referring to FIGURES 7 and 9, each turntable comprises a circular disk 67 having a hub 68 journaled by ball-bearings 70 upon a vertical shaft 71. Shaft 71 is mounted in a bracket 72 rising from the frame 24 of the machine. The disk 67 includes a bevel gear 73 (FIGURE 9) journaled on vertical shaft 71 and pinned as at 74 to the turntable disk 67.

In order to impart rotary motion to the turntable, the bevel gear 73 is in mesh with a bevel gear 75 which is pinned as at 76 to cross shaft 54. As described earlier, cross shaft 54 carries the idler sprockets 53—53 of the switchback conveyor run 14, which drives turntable 16.

The conveyor chains 37—37, which are advanced by the motor 27, thus drive shaft 54; shaft 54, by way of bevel gears 73 and 75 impart rotary motion to the turntable 16 at a speed correlated with the lineal motion of the switchback conveyor run 14.

In order to advance the upstream conveyor run 13 in time with the switchback run 14, there is provided a second or driven bevel gear 77 pinned as at 78 to the cross

shaft 80 which carries the drive sprockets 81—81 previously noted (FIGURE 9). The sprockets 81 thus drive the upstream conveyor run 13 at a speed identical with the speed of the switchback run 14.

As the books advance along the conveyor runs toward the turntables (for example, conveyor run 13 toward turntable 16—FIGURE 2), the leading edge of each book is elevated by the paddle wheel 69, located in a position generally tangent to the turntable (FIGURE 7). A second paddle wheel 82 is located at the opposite side of the turntable 16. Both paddle wheels 69 and 82 are rotated by chain drives 83 and 84 (FIGURES 4, 7 and 8). Chain drive 83 includes a sprocket 85 keyed to the cross shaft 54 (FIGURE 9). The other chain drive 84 includes a sprocket 86 keyed to shaft 80.

Each chain drive 83 and 84 includes a chain 87 meshing with the sprockets 88 and 90 of the paddle wheel shafts 91—91 of the paddle wheels 69 and 82. The cross shafts 91 are journaled in bearing blocks 92 which are mounted upon the frame 24 of the machine.

As illustrated in FIGURE 6 the first paddle wheel A, indicated previously at 69, lifts the books from the first conveyor run 13 to the turntable 16 which is arranged to move the book through an arc of 180°. The second paddle wheel B, also indicated at 82, is also located for rotation in a position generally tangent to the turntable so as to carry the books from the turntable 16 and to deposit the books upon the switchback run 14. The second turntable 17 is similarly provided with identical paddle wheels C and D in driving connection with the conveyor system and rotating in time with the conveyor system and turntable 17 for the same purpose.

Described in detail (FIGURES 12 and 13), each paddle wheel 69 or 82 comprises a cylindrical hub 93 secured to shaft 91 by means of a set screw 94. The hub includes a series of generally U-shaped brackets 95 secured by screws 96 to the periphery of hub 93. The U-shaped brackets 95 provide respective limbs 97 which project radially from the axis of rotation of shaft 91 upon which hub 93 is mounted.

In order to elevate the books from the surface of the conveyor run (for example run 13, indicated in broken lines in FIGURE 13), each paddle wheel is provided with radial vanes 98 which are attached to the limbs 97 by means of screws 100. The vanes 98 are formed from a resilient material, such as a soft plastic or rubber in order to provide frictional engagement with the rounded end 45 of the book.

As best shown in FIGURE 13, the paddle wheel 69 is mounted for rotation at an elevation (shaft 91) whereby the periphery E (shown in broken lines) of the paddle wheel intercepts and rises above the top surface of the conveyor run 13. It will be noted in this view, that the turntable 16 is located in a horizontal plane above the surface of conveyor run 13 as at F in FIGURE 13.

Accordingly, as a given book, indicated at G in broken lines (FIGURE 13) advances to the paddle wheel, its leading end H is engaged by one of the vanes 98 of the paddle wheel and is elevated as indicated in broken lines. The vanes 98 of the paddle wheel, through continued rotation, elevate and advance the book in a path generally tangent to the rotating turntable 16 so as to deposit the book upon the turntable, with the book resting upon its rounded edge 45.

The book is then carried by the turntable through its arc for deposit upon the next conveyor run. The motion of the book upon reaching the next run of the conveyor is similar to that indicated in FIGURE 13. However, at the discharge point, the paddle wheel, which is rotating in the opposite direction, engages the rounded end 45 of the block, elevates it from the turntable and advances it in a generally tangential path from the turntable to the next run of the conveyor.

Adjustable arcuate guides

Upon being elevated to the turntable 16 by the paddle wheel 69, each book is engaged by the arcuate guideway, previously indicated generally at 57 (FIGURE 7), extending through an arc of approximately 180° above the turntable 16. A similar guideway is mounted with reference to the second turntable 17. The arcuate guideway 57 has opposite ends connected to the longitudinal guideways 56 so as to control the path of motion of the books as they pass from one conveyor run to the turntable for movement through an arc to the next conveyor run.

In order to accommodate for the various book sizes, each arcuate guideway 57 (FIGURE 7) is of adjustable design. As best shown in FIGURE 7, each arcuate guideway 57 comprises an outer arcuate band 101 formed of flexible material and bent to an arc corresponding generally to the radius of the turntable. The opposite ends of the band 101 adjoin the longitudinal guide plates 58 and are held in position with respect to the ends of the guide plates 58 by means of mounting blocks 102—102.

As noted earlier, the longitudinal guide plates 58 are mounted for adjustment transversely to accommodate for the thickness of the books which are advanced through the apparatus. When the outer longitudinal guide plates 58 are adjusted transversely, the adjoining ends of the arcuate band 101 are shifted in unison therewith. In addition, the radius of the arcuate band 101 also is adjustable with reference to the longitudinal guide rails 58 to accommodate the size of the books.

Described in detail, the mounting blocks 102—102 (FIGURE 7), which support the arcuate band 101 are secured rigidly to the end portions of band 101 at opposite ends thereof. Each mounting block 102, in turn, includes a support rod 103. Each support rod 103 slidably passes through a clamping block 104 which is attached to the end portion of the companion outer longitudinal guide plate 58. Each clamping block 104 includes a thumb screw 105 which engages the support rod 103. By virtue of this arrangement, the end portions of the arcuate band 101 are shifted transversely with the outer guide plates 58 when the apparatus is adjusted to accommodate a given book size. In addition, the radius of the flexible band 101 may be adjusted by loosening the thumb screws 105, then shifting the position of the arcuate band 101 longitudinally with reference to the outer guide plates 58.

The arcuate passageway 57 further includes an inner arcuate band 106 (FIGURE 7) which forms a continuation of the inner longitudinal guide plate 58. The inner band 106 is also formed of flexible material and is adapted to shift transversely in unison with the inner longitudinal guide plates 58 when the apparatus is adjusted for a run of given size books. The radius of the inner band 106 is also adjustable in the same manner outlined above with reference to the outer band 101.

For this purpose the opposite ends of each inner band 106 are connected to the inner guide plate 58 for transverse adjustment therewith. In addition, the end portions of the inner band 106 are arranged for longitudinal adjustment with reference to the inner longitudinal guide plates 58, thereby to vary the radius of the inner band in accommodating the size of the books for which the machine is adjusted.

Described in detail (FIGURE 7) each end of the inner band 106 includes a mounting block 107. Each mounting block 107 includes a support rod 108 slidably passing through a bore formed in a clamping block 110, which is attached to the end portion of the companion inner longitudinal guide plate 58. The clamping block 110 includes a thumb screw 111 engageable with the support rod 108 and adapted to clamp the mounting block 107 and inner flexible band 106 in an adjusted position. By virtue of this arrangement, the inner arcuate band 106

shifts transversely with the inner longitudinal guide plates 58 upon adjustment thereof, and the radius of the inner band 106 may be varied, as required, by adjusting the support rods 108 with reference to the clamping blocks 110.

Having described my invention I claim:

1. A book drying apparatus for applying heat to assembled and freshly glued books comprising:
a frame structure;
a plurality of conveyor runs angularly related to one another and mounted for lineal advancement along said frame structure;
said conveyor runs comprising an upstream run and at least one downstream run;
each conveyor run having a book-receiving end and a book-discharge end;
said upstream conveyor run adapted to receive said freshly glued books;
the discharge end of the upstream conveyor run being disposed adjacent the receiving end of the downstream run;
a turntable rotatably journaled for rotation about a generally vertical axis adjacent the discharge end of the upstream conveyor run and the receiving end of the downstream conveyor run;
power means in driving connection with said conveyor runs for advancing the same lineally and for imparting rotary motion to the turntable in a direction to advance the books in an arcuate path from the discharge end of the upstream conveyor run to the receiving end of the downstream run.
2. A book drying apparatus for applying heat to assembled and freshly glued books comprising:
a frame structure;
a plurality of conveyor runs angularly related to one another and mounted for lineal advancement along said frame structure;
said conveyor runs comprising an upstream run and at least one downstream run;
each conveyor run having a book-receiving end and a book-discharge end;
said upstream conveyor run adapted to receive said freshly glued books;
the discharge end of the upstream conveyor run being disposed adjacent the receiving end of the downstream run;
heating elements mounted relative to at least one of said conveyor runs and adapted to project heat upon the books advancing along said conveyor run;
a turntable rotatably journaled for rotation about a generally vertical axis adjacent the discharge end of the upstream conveyor run and the receiving end of the downstream conveyor run;
power means in driving connection with said conveyor runs for advancing the same lineally and for imparting rotary motion to the turntable in a direction to advance the books in an arcuate path from the discharge end of the upstream conveyor run to the receiving end of the downstream run.
3. A book drying apparatus for applying heat to freshly glued books having rounded ends comprising:
a frame structure;
a plurality of conveyor runs angularly related to one another and mounted for lineal advancement along said frame structure;
said conveyor runs comprising an upstream run advancing in a first direction and at least one downstream run advancing in a second direction;
each conveyor run having a book-receiving end and a book-discharge end;
said upstream run adapted to receive said freshly glued books with the rounded ends of the books resting upon the conveyor run;

the discharge end of the upstream conveyor run being disposed adjacent the receiving end of the downstream run;

heating elements mounted beneath said conveyor runs and adapted to project heat upon the rounded ends of the books advancing along said conveyor runs; a turntable rotatably journaled for rotation about a generally vertical axis adjacent the discharge end of the upstream conveyor run and the receiving end of the downstream conveyor run; power means in driving connection with said conveyor runs for advancing the same lineally and for imparting rotary motion to the turntable in a direction corresponding to the direction of advancement of said conveyor runs; said turntable adapted to advance the books in an arcuate path from the discharge end of the upstream conveyor run to the receiving end of the downstream run; and respective pairs of longitudinal guide plates rising upwardly from the opposite sides of said conveyor runs and adapted to slidably confine the books in generally upright position with rounded ends thereof of resting upon the conveyor runs.

4. A book drying apparatus for applying heat to freshly glued books having rounded ends comprising:

a frame structure;
a plurality of conveyor runs angularly related to one another and mounted for lineal advancement along said frame structure;
said conveyor runs comprising an upstream run advancing in a first direction and at least one downstream run advancing in a second direction;
each conveyor run having a book-receiving end and a book-discharge end;
said upstream run adapted to receive said freshly glued books with the rounded ends of the books resting upon the conveyor run;
the discharge end of the upstream conveyor run being disposed adjacent the receiving end of the downstream run;
heating elements mounted beneath said conveyor runs and adapted to project heat upon the rounded ends of the books advancing along said conveyor runs; a turntable rotatably journaled for rotation about a generally vertical axis adjacent the discharge end of the upstream conveyor run and the receiving end of the downstream conveyor run;
power means in driving connection with said conveyor runs for advancing the same lineally and for imparting rotary motion to the turntable in a direction corresponding to the direction of advancement of said conveyor runs; said turntable adapted to advance the books in an arcuate path from the discharge end of the upstream conveyor run to the receiving end of the downstream run; respective pairs of longitudinal guide plates rising upwardly from the opposite side of said conveyor runs and adapted to slidably confine the books in generally upright position with rounded ends thereof resting upon the conveyor runs; and inner and outer arcuate guide plates extending around the turntable in positions generally concentric to the axis of rotation of the turntable, said arcuate guide plates having end portions interconnected to the end portions of said longitudinal guide plates of the upstream and downstream runs of the conveyor system and adapted to guide the books in an arcuate path from the downstream end of one pair of longitudinal guide plates to the upstream end of the second pair of longitudinal guide plates.

5. A book drying apparatus for applying heat to freshly glued books having rounded ends comprising:
a frame structure;

a plurality of conveyor runs angularly related to one another and mounted for lineal advancement along said frame structure;

said conveyor runs comprising an upstream run advancing in a first direction and at least one downstream run advancing in a second direction;

each conveyor run having a book-receiving end and a book-discharge end;

said upstream run adapted to receive said freshly glued books with the rounded ends of the books resting upon the conveyor run;

the discharge end of the upstream conveyor run being disposed adjacent the receiving end of the downstream run;

heating elements mounted beneath said conveyor runs and adapted to project heat upon the rounded ends of the books advancing along said conveyor runs;

a turntable rotatably journaled for rotation about a generally vertical axis adjacent the discharge end of the upstream conveyor run and the receiving end of the downstream conveyor run;

power means in driving connection with said conveyor runs for advancing the same lineally and for imparting rotary motion to the turntable in a direction corresponding to the direction of advancement of said conveyor runs;

said turntable adapted to advance the books in an arcuate path from the discharge end of the upstream conveyor run to the receiving end of the downstream run;

respective pairs of longitudinal guide plates rising upwardly from the opposite sides of said conveyor runs and adapted to slidably confine the books in generally upright position with rounded ends thereof resting upon the conveyor runs;

means for adjusting the said longitudinal guide plates transversely relative to one another, thereby to accommodate the drying apparatus to books of different thicknesses;

and inner and outer arcuate guide plates extending around the turntable in positions generally concentric to the axis of rotation of the turntable, said arcuate guide plates having end portions interconnected to the end portions of said longitudinal guide plates of the upstream and downstream runs of the conveyor system and adapted to guide the books in an arcuate path from the downstream end of one pair of longitudinal guide plates to the upstream end of the second pair of longitudinal guide plates.

6. A book drying apparatus for applying heat to freshly glued books having rounded ends comprising:

a frame structure;

a plurality of conveyor runs angularly related to one another and mounted for lineal advancement along said frame structure;

said conveyor runs comprising an upstream run and at least one downstream run;

each conveyor run having a book-receiving end and a book-discharge end;

said upstream run adapted to receive said freshly glued books with the rounded ends of the books resting upon the conveyor run;

the discharge end of the upstream conveyor run being disposed adjacent the receiving end of the downstream run;

heating elements mounted beneath said conveyor runs and adapted to project heat upon the rounded ends of the books advancing along said conveyor runs;

a turntable rotatably journaled for rotation about a generally vertical axis adjacent the discharge end of the upstream conveyor run and the receiving end of the downstream conveyor run;

power means in driving connection with said conveyor runs for advancing the same lineally in the same direction relative to the frame;

power means in driving connection with the turntable adapted to impart rotary motion to the turntable in a direction corresponding to the direction of advancement of said conveyor runs;

said turntable adapted to advance the books in an arcuate path from the discharge end of the upstream conveyor run to the receiving end of the downstream run;

respective pairs of longitudinal guide plates rising upwardly from the opposite sides of said conveyor runs and adapted to slidably confine the books in generally upright position with rounded ends thereof resting upon the conveyor runs;

inner and outer arcuate guide plates extending around the turntable in positions generally concentric with the axis of rotation of the turntable, said arcuate guide plates having end portions interconnected to the end portions of said longitudinal guide plates of the upstream and downstream runs of the conveyor system;

and adjustment means connected to said inner and outer guide plates adapted to change the radius thereof, thereby to adapt the guide plates to books of various sizes for advancement around the turntable.

7. A book drying apparatus as set forth in claim 5 in which there is provided adjustment means interconnecting the end portions of the longitudinal guide plates to the end portions of the inner and outer arcuate guide plates, adapting said inner and outer arcuate guide plates to be shifted relative to the end portions of the longitudinal guide plates, thereby to change the radius of said inner and outer arcuate guide plates to accommodate books of various sizes for advancement about the turntable.

8. A book drying apparatus as set forth in claim 1 in which the power means is in driving connection with said downstream conveyor run and in which there is provided a transmission unit in driving connection between the downstream conveyor run and the turntable for imparting rotary motion to the turntable at a peripheral speed substantially equal to the lineal speed of the downstream conveyor run.

9. A book drying apparatus as set forth in claim 8 in which the transmission unit which interconnects the turntable to said downstream run of the conveyor includes driving means interconnecting the turntable with the upstream run of the conveyor, whereby said downstream run, said turntable, and said upstream conveyor run all advance in the same direction and at a substantially uniform lineal speed.

10. A book drying apparatus as set forth in claim 1 in which there is provided a paddle wheel interposed between the discharge end of the upstream conveyor run and turntable;

said paddle wheel being mounted for rotation about a horizontal axis relative to the vertical axis of rotation of the turntable;

and driving means interconnecting said paddle wheel with said conveyor runs for rotating the paddle wheel in the same direction as said conveyor runs and turntable;

said paddle wheel adapted to advance the books from the discharge end of the upstream conveyor run to the turntable.

11. A book drying apparatus as set forth in claim 1 in which there is provided a first paddle wheel interposed between the discharge end of the upstream conveyor run and a second paddle wheel interposed between said turntable and the book-receiving end of the downstream conveyor run;

said paddle wheels being mounted for rotation about respective horizontal axes relative to the vertical axes of rotation of the turntables;

15

and driving means interconnecting said paddle wheels with said conveyor runs for rotating the paddle wheels in the same direction as said conveyor runs and turntable;

said paddle wheels adapted to advance the books from the discharge end of the upstream conveyor run to the turntable and from the turntable to the receiving end of the downstream conveyor run.

12. A book drying apparatus as set forth in claim 3 in which each conveyor run comprises a pair of chains spaced transversely from one another;

each of said pair of chains having transverse book support bars spaced apart longitudinally from one another;

said transverse book support bars adapted to engage and support the rounded ends of the books for advancement about said heating elements, whereby the freshly glued rounded ends of the books are exposed to said heating elements during advancement along said conveyor runs.

13. A book drying apparatus as set forth in claim 2 in which said conveyor runs are disposed generally in V-shaped formation and in which the turntable is disposed adjacent book discharge end of said upstream conveyor run and the book-receiving end of the downstream conveyor run at the apex of said V-shaped formation.

14. A book drying apparatus as set forth in claim 2 in which the plurality of conveyor runs are generally of zigzag formation comprising:

an upstream run;
switchback run;

16

a downstream run, said conveyor runs being generally parallel with one another; and respective turntables rotatably journaled for rotation about generally vertical axes adjacent the discharge end of one conveyor run and the receiving end of the companion conveyor run.

15. A book drying apparatus as set forth in claim 2 in which the conveyor system comprises:

an upstream conveyor run;

10 a downstream conveyor run extending generally parallel with said upstream conveyor run;

a transverse conveyor run extending from the book-discharge end of the upstream run to the book-receiving end of said downstream run;

15 a first turntable journaled for rotation about generally vertical axis adjacent the discharge end of the upstream conveyor run and the book-receiving end of said transverse conveyor run;

and a second turntable mounted for rotation about a generally vertical axis adjacent the book-discharge end of said transverse conveyor run and the book-receiving end of said downstream run.
